S. J. STRID

DRAFT GEAR

Filed March 13, 1926

Inventor
Sven J. Strid
By Wallace R. Law Atty.

UNITED STATES PATENT OFFICE.

SVEN J. STRID, OF CHICAGO, ILLINOIS, ASSIGNOR TO ROY J. COOK, OF CHICAGO, ILLINOIS.

DRAFT GEAR.

Application filed March 13, 1926. Serial No. 94,393.

This invention relates to improvements in draft gears and has for an object to provide a new and improved form of draft gear, wherein increasing resistance will be offered to the movements of the coupler butt, or the like, under draft and buffing strains. Other objects reside in the provision of an easily assembled, economical and efficient mechanism by which a relatively great resistance will be presented for a comparatively short travel of the coupler body.

5 Other objects will be more fully set forth and described in the following specification and shown in the accompanying drawing,

10 15 in which—

Figure 1 is a vertical section through an embodiment of my invention, the coupler butt and shank being indicated in full line.

Fig. 2 is a vertical section taken along the line 2—2 of Fig. 1.

Fig. 3 is a similar view taken along the line 3—3 of Fig. 1.

10, 10 indicate generally spaced draft sills having draft lugs 11 secured thereto and projecting therefrom in well known manner. 12 indicates a conventional form of coupler having a butt 12^a fitting the hooded end 13^a of the yoke 13, which extends rearwardly from the hooded end, as shown in Fig. 1. 15 This yoke and the included draft gear may be supported by cross straps 15, or in any suitable manner. A key-block 17 co-acts with the hooded end of the yoke 13 to retain the coupler 12 against withdrawal from the yoke in the particular form illustrated, although it is to be understood that details of the coupler butt, yoke and securing means may be varied as desired, as my invention resides in the draft gear itself rather than 20 in the elements mentioned.

40 Located at the rear of the coupler butt 12^a is a follower 19 of conventional construction.

The draft gear itself includes the socket member 20, open at the front end and closed at the rear end as indicated at 20^a. The closed end 20^a of the socket 20 contacts with the rear end of the yoke 13, as shown in Fig. 1, for example. Mounted in the forward portion of the socket 20 at the top and bottom thereof, are the slide plates 27 and 28 formed with the inwardly projecting end portions 27^a and 28^a respectively. The plates 27 are appreciably less in length than the sockets 20, or are so arranged that their rear ends terminate some distance short of

the closed end of the socket 20, and a coiled spring 30 is located in the socket between the inner ends of the plates 27 and 28 and the closed end 20^a of the socket.

Located between the slide plates 27 and 28 and spaced therefrom, is the plunger member 32 having the tapered ends 32^a and 32^b at front and back, respectively. Intermediate the tapered portions are the recesses 32^c. The plunger ends are also cored out, 65 as indicated at 32^e for lightness.

Interposed between the slide plates 27, 28 and the front 22^a of the plunger 22 are the upper and lower wedge blocks 35 and 36, respectively, while at the rear end 32^b of 70 the plunger are provided the upper and lower wedge blocks 37, 38, respectively. Each of these blocks is provided with a portion α projecting from one of the recesses 32^c, the adjacent ends of the upper wedge blocks 75 and the lower wedge blocks being spaced apart. The coiled spring 39 is mounted between adjacent ends of each pair of wedge blocks in the recesses 32^c as clearly shown in Figs. 1 and 2 of the drawings.

The rear end of the plunger 32^b is enlarged to form a head 32^g which is joined to the tapered portion 32^b by a reduced neck 32^f. This head 32^g is shouldered to form a seat for the coiled spring 41 which extends therefrom to the end 20^a of the socket member 20, a central seating lug 20^d serving to properly position this spring at its rear end.

The rear ends of the wedge blocks 37 and 38 are grooved or cut away as indicated by γ 80 to form a seat for the coiled spring 45, which extends therefrom to the end wall 20^a of the socket 20, this spring being relatively the strongest of the three rear end springs.

The wedge blocks 35, 36, 37 and 38 all have 95 their inner sides inclined to contact with the converging surfaces of the tapered plunger ends 32^a and 32^b, the interposed coiled springs 39 functioning normally to maintain the wedge blocks in separated relation, as 100 shown in Fig. 1.

In the operation of the device, assuming a buffing strain is to be imparted to the coupler shank 12, the coupler will be moved inwardly with respect to the yoke 13, carrying with it the follower 19 and shifting the elements of the draft gear inwardly with respect to the socket 20 which is held against shift by the yoke which, in turn, is held against such movement by the draft lugs 11. 110

This movement is resisted by the springs 30, 41 and 45. The resistance offered by spring 45 to the movement of wedge blocks 37 and 38 is greater than that of springs 30 and 41 to the movements of members 27, 28 and plunger 32 respectively, due to the greater strength of the former spring and this will set up an increased frictional resistance between wedge blocks 37, 38, plunger end 32^a and slide plates 27, 28. This tends to separate the slide plates and increases the friction between such plates and the top and bottom of the socket 20. At the same time, the resistance of spring 41 to the movement of plunger 32 enhances the frictional contact between the front wedge blocks 35 and 36, the plunger end 32^a and the slide plates 27, 28, which are thereby subjected to an added spreading action, further increasing the friction between such plates and the walls of socket 20.

In this manner, all the relatively movable parts being subjected to an increasing wedging action, it will be found that resistance to movement of the coupler butt will be greatly increased during its travel from normal or neutral position, although such movement is amply cushioned by the coiled springs which interpose a yielding resistance but which also multiply the resistance offered by the friction members.

The action is similar under draft strains save that the coupler butt picks up the yoke 13 and moves it and the other movable members by the interposed springs 30, 41 and 45, the resistance to draft movement being otherwise similar to the resistance of the buffing movement. During the draft movement, the follower 19 prevents longitudinal movement of the slide plates 27, 28, but in lieu of moving these the socket member 20 moves, and the relative movement and resistances are the same as above described.

It will be apparent that my invention is susceptible of modification and I do not wish to be restricted to the form shown and described, except as defined in the appended claims.

What I claim is:

50 1. A socket member, a pair of slide members slidably mounted therein, a plunger tapered at each end, a wedge block between

each tapered end and one of said slide members, means to yieldingly resist movement of said slide members, plunger and blocks, said blocks being spaced apart, means yieldingly maintaining said blocks in normal spaced relation, said last named means comprising a coiled spring said plunger being recessed to accommodate said spring.

2. A socket member, a pair of slide members slidably mounted therein, a plunger tapered at each end, a wedge block between each tapered end and one of said slide members, means to yieldingly resist movement of said slide members, plunger and blocks, said blocks being spaced apart, means yieldingly maintaining said blocks in normal spaced relation, said last named means comprising coiled springs, said plunger being recessed to accommodate said springs, said blocks being provided with means extending into said recess.

3. A socket member, a pair of slide members slidably mounted therein in contact with the walls thereof, a plunger located between said slide members and spaced therefrom, said plunger being provided with spaced tapered portions, wedge blocks interposed between said tapered portions and said slide members, the members of each pair of said wedge blocks being normally spaced apart, a spring interposed between said spaced wedge blocks and means to yieldingly resist the movement of said slide members, wedge blocks and plunger.

4. A socket member, a pair of slide members slidably mounted therein in contact with the walls thereof, a plunger located between said slide members and spaced therefrom, said plunger being provided with spaced tapered portions, wedge blocks interposed between said tapered portions and said slide members, means to yieldingly resist movement of said slide members and wedge blocks, the members of each pair of said wedge blocks being normally spaced apart, and a spring interposed between said spaced wedge blocks, said plunger being recessed to accommodate said springs.

In witness whereof, I hereunto subscribe my name to this specification.

SVEN J. STRID.
